UNITED STATES PATENT OFFICE.

JOHN T. KELLY, OF BROOKLYN, NEW YORK.

DESIGN FOR A PIPE-COUPING.

SPECIFICATION forming part of Design No. 20,236, dated October 28, 1890.

Application filed July 28, 1890. Serial No. 360,248. Term of patent 14 years.

To all whom it may concern:

Be it known that I, JOHN T. KELLY, a resident of Brooklyn, in the county of Kings and State of New York, have invented a new and original Design for Pipe-Couplings; and I do hereby declare the following to be a full, clear, and exact description thereof.

Figure 1 is a perspective view of a coupling illustrating my design, and Fig. 2 is a longitudinal section thereof.

My design consists in a coupling for pipes having collars at each end, an angular central portion, and depressed cylindrical portions between said central angular portion and said outer collars.

In the drawings, *a* is the central angular portion, this portion being formed of a series of flat faces forming angles *c* where they

meet each other. At the ends of the coupling are the collars *d*, and between the collars *d* and the central angular portion are the depressed cylindrical portions or rings *e*. The coupling thus presents to the eye a tubular coupling having depressed rings on each side of a central portion having a series of flat faces.

What I claim is—

The design for a pipe-coupling herein shown and described.

In testimony whereof I, the said JOHN T. KELLY, have hereunto set my hand.

JNO. T. KELLY.
